UNITED STATES PATENT OFFICE.

WALENTY SZABAT, OF DEPUE, ILLINOIS.

HOROLOGICAL DEVICE.

1,252,735.

Specification of Letters Patent.

Patented Jan. 8, 1918.

Application filed February 16, 1917. Serial No. 148,934.

To all whom it may concern:

Be it known that I, WALENTY SZABAT, a subject of the Czar of Russia, and a resident of Depue, in the county of Bureau and State of Illinois, have invented certain new and useful Improvements in Horological Devices, of which the following is a specification.

This invention relates to improvements in horological devices and particularly to types depending for accuracy on natural light and commonly known as sun dials.

The principal object of the invention is to provide an instrument of this type which may be compactly folded and carried in the pocket or extended when it is desired to determine the time by observation of the indications obtained.

A second object is to combine the sun dial with a time piece or watch and to further combine within the casing a compass whereby the setting of the sun dial device may be accurately performed, and finally, to provide the entire device in a form which may be inclosed within the walls of an ordinary watch case.

These objects are attained by the novel combination and construction of parts hereafter described and shown in the accompanying drawing, in which:—

Fig. 1 is a perspective view showing the device extended in position for determining time.

Fig. 2 is a plan view of the same, also in an open position.

Fig. 3 is a perspective view showing a detail of construction.

Fig. 4 is a plan view similar to that of Fig. 2, but showing the sun dial index removed.

Fig. 5 is a front elevation showing the case opened and the compass folded.

Fig. 6 is a side elevation showing both cases folded and the watch dial as viewed from the exterior of the casing.

Fig. 7 is a plan view of the sun dial index.

Fig. 8 is a perspective view of a detail of construction, and

Fig. 9 is a similar perspective view showing another detail.

In the several views, the bezel of the casing is indicated by the numeral 15 and is shown to be of the usual watch case construction provided with an inner rear cover 16, and outer cover 17 secured in the usual manner, as is also the ring 14 and knurled

winding knob 18. The front cover 20 is formed with a circular aperture having an eccentrically disposed transparent plate 21 in register with the watch dial 22, so that the minute and hour hands, respectively 23 and 24, may be seen in connection with the numerals disposed on the face of the dial 22, even if the cover 20 be closed.

Below the watch dial 22 is pivotally mounted a compass 28 by means of pivots 29 attached within the casing in such manner that when not required the compass may stand parallel to the covers, but when it is desired to use the device as a sun dial, the compass is turned into the position shown in Fig. 1, so that the pointer may accurately indicate the direction in which the device must be placed, so that the shadow from the post 30 will fall correctly with respect to the sun dial index 32.

This post is engaged at its lower end to an arcuate slide 33 by means of the clamp element 34, the slide operating in a slot 35 formed in a sector shaped element 36 engaged in a frame 38 secured to the outer casing 20.

Thus the post 30 when not in use may be moved laterally to one edge of the casing 20 and then folded so that the cover or lid 20 may be closed. When erected in the position shown in Fig. 1, it is held in position by means of a spring 39 attached to the element 36. The dial 32, as shown in Fig. 7, is semi-circular in outline and divided into ten equal portions by radial lines 40 extending from its periphery inward to the numerals 41, which are indicative of the hours at which observation is taken.

In order to distinguish lesser periods of time than full hours, oblique lines 42, cross uniformly spaced circular lines 44, formed concentrically upon the margin of the dial 32, by means of which periods of time of five minutes can be accurately differentiated.

In operation, the covers 17 and 20 are extended at length forming a base from which the body extends vertically, the same containing the compass 28 which is turned horizontally, parallel with the disposition of the covers so that the entire device may be turned axially to bring the needle or index of the compass into such position as to point north; the slide 33 is then moved to bring the base of the post 30 substantially central of the cover 20 and then the post is erected, whereupon its shadow will fall upon the index 32.

the position of the shadow indicating the hour and fraction of the exact time.

Having thus described my invention, what I claim as new and desire to secure by Letters Patent, is:—

1. In a horological implement, the combination with a short cylindrical casing provided with hinged covers upon each side, of a segmental plate secured in one of said covers, a slide operable in said plate, a post hingedly attached to said slide, means for holding said post when in an erect position, a dial secured to said casing with reference to said post, said dial indicating hours and fractions thereon, and a compass pivotally mounted in said casing disposable in either a vertical or horizontal position therewithin, said covers being adapted to protect the elements therewithin when closed.
2. In a horological implement, the combination with a circular case having hinged covers on each side thereof, of a collapsible post secured in one of said covers, means for maintaining said post in an erect position, a scale arranged on said cover with relation to said post, said scale having a plurality of radial lines, circular lines concentric to the exterior of said scale and oblique lines disposed between the radial lines crossing said concentric lines whereby time may be ascertained in hours and subdivisions thereof through the shadow of said post, and a compass pivotally mounted in said case by means of which the case may be properly positioned.

3. In a horological implement, the combination with a circular case having hinged covers on each side thereof, of a collapsible post secured in one of said covers, means for maintaining said post in an erect position, a scale arranged on said cover with relation to said post, said scale having a plurality of radial lines, circular lines concentric to the exterior of said scale and oblique lines disposed between the radial lines crossing said concentric lines whereby time may be ascertained in hours and subdivisions thereof through the shadow of said post, and a compass pivotally mounted in said case by means of which the case may be properly positioned.

Signed at Depue, in the county of Bureau, and State of Illinois, this seventh day of February 1917.

WALENTY SZABAT.
